(57) **CLAIM**

The ornamental design for a handle for a rapid transfer port, as shown and described.

DESCRIPTION

FIG. 1 is a front left side perspective view of a handle for a rapid transfer port.

FIG. 2 is a front right side perspective view of the handle of FIG. 1.

FIG. 3 is a front view of the handle of FIG. 1.

FIG. 4 is a left side view of the handle of FIG. 1.

FIG. 5 is a right side view of the handle of FIG. 1.

FIG. 6 is a top view of the handle of FIG. 1; and,

FIG. 7 is a bottom view of the handle of FIG. 1.

The broken lines in the drawings illustrate portions of the handle for a rapid transfer port that form no part of the claim. The labels used herein to describe orientation (e.g., front, rear, left, right) are merely for reference and are not intended to limit the interpretation of the design.
